UNITED STATES PATENT OFFICE.

JOHN F. O'CONNOR, OF CHICAGO, ILLINOIS, ASSIGNOR TO W. H. MINER COMPANY, OF CHICAGO,
ILLINOIS, A CORPORATION OF ILLINOIS.

DRAW-BAR AND YOKE CONNECTION FOR RAILWAY DRAFT-RIGGING.

No. 918,583.

Specification of Letters Patent. Patented April 20, 1909.

Application filed October 21, 1907. Serial No. 398,346.

To all whom it may concern:

Be it known that I, JOHN F. O'CONNOR, a citizen of the United States, residing in Chicago, in the county of Cook and State of Illinois, have invented a new and useful Improvement in Draw-Bar and Yoke Connections for Railway Draft-Rigging, of which the following is a specification.

My invention relates to improvements in means for connecting the draw bar of car couplers to the yoke.

Heretofore the draw bar strap or yoke has ordinarily been connected to the rear end of the draw bar of the coupler by one or more vertical rivets passing through the draw bar and yoke, and difficulty is experienced in practical operation from the rivets shearing under pulling or buffing strains, and because when the parts are thus riveted together it requires time and labor to cut the rivets when necessary to remove and replace the coupler or draw bar.

The object of my invention is to provide a draw bar and yoke connection of a strong, simple, efficient and durable connection, which will enable the connecting rivets to be done away with, and which will at the same time give much additional strength, rigidity and security, while enabling the draw bar and yoke to be quickly and conveniently disconnected when removal, replacement or repairs are necessary.

My invention consists in the means I employ to practically accomplish this object or result as herein shown and described and more particularly specified in the claims, the same consisting essentially, in connection with the draw bar, its yoke and the front draft rigging follower, in a connecting sleeve or band surrounding the rear end of the draw bar and the front end of the draw bar yoke, and abutting at its front end against shoulders on the draw bar, and at its rear end against the front follower, the draw bar and yoke being provided with interengaging shoulders to prevent movement of one in respect to the other when surrounded by said connecting band or sleeve.

In the accompanying drawing, forming a part of this specification, Figure 1 is a side elevation, partly in longitudinal section, of a draw bar and yoke connection embodying my invention; Fig. 2 is a detail plan view; Fig. 3 is a vertical cross section on line 3—3 of Fig. 1; and Fig. 4 is a detail horizontal sec-

tion on line 4—4 of Fig. 1, the follower being shown in plan.

In the drawing A represents the draw bar, B the yoke, C the front follower of the draft rigging and D the connecting sleeve or band surrounding the front end of the draw bar yoke and the rear end of the draw bar. The draw bar A is provided at its rear end, on its upper and lower faces, with a groove a^1 forming front and rear shoulders a^1 a^2 to receive and engage coöperating gibs or shoulders b at the front end of the upper and lower limbs of the draw bar yoke or strap B. The draw bar A is also provided on its upright sides or faces with shoulders or abutments a^3 for the front end of the connecting sleeve or band D to abut against. At its rear end the connecting sleeve D abuts against the front follower C of the draft rigging. The connecting sleeve or band D is shaped to snugly fit and surround the draw bar and yoke; and, when driven or forced into place after the draw bar and yoke are assembled, it will snugly bind and clamp the parts together. While the fit of the connecting sleeve should be tight and snug so as to require forcing or driving to slip it into place, it need not however be so tight a fit as to require shrinking or to interfere with the quick and ready disconnection of the parts by simply first removing the front follower and other parts of the draft rigging and then driving or forcing the connecting sleeve backward over the draw bar yoke.

The shoulders a^3 on the upright sides or faces of the draw bar for the connecting sleeve to abut against, are preferably formed by simply providing the draw bar with a reduced portion a^4 at its rear end in horizontal dimension.

E represents the draft rigging spring and F F¹ friction blocks, G a friction shell or case, H the rear follower and K K¹ front and rear stops for the followers.

I claim:

1. The combination with a draw bar, of a draw bar yoke having upper and lower limbs embracing the draw-bar between them, the front draft rigging follower, a connecting sleeve surrounding the yoke and draw bar, the draw bar and yoke having interengaging shoulders, and the draw bar having shoulders for the front end of the connecting sleeve to abut against, said connecting sleeve abutting at its rear end against the front follower, substantially as specified.

2. The combination with a draw bar and its yoke the yoke having two limbs embracing the draw-bar between them, of a connecting sleeve surrounding the rear end of the draw bar and the front end of the yoke, the draw bar and yoke having interengaging shoulders, and the draw bar having a shoulder for the front end of the sleeve to abut against, substantially as specified.

10 3. The combination with the draw bar and

yoke having interengaging shoulders the yoke having two limbs embracing the draw-bar between them, of a connecting band surrounding the draw bar and yoke, substantially as specified.

JOHN F. O'CONNOR.
